UNITED STATES PATENT OFFICE.

WILLIAM J. KILPATRICK, OF DETROIT, MICHIGAN, ASSIGNOR TO BURROUGHS ADDING MACHINE COMPANY, OF DETROIT, MICHIGAN, A CORPORATION OF MICHIGAN.

ADDING AND LISTING MACHINE.

996,260.

Specification of Letters Patent. Patented June 27, 1911.

Application filed September 19, 1908. Serial No. 453,776.

To all whom it may concern:

Be it known that I, WILLIAM J. KILPATRICK, a citizen of the United States, residing at Detroit, in the county of Wayne and 5 State of Michigan, have invented certain new and useful Improvements in Adding and Listing Machines, of which the following is a specification.

This invention relates to that class of 10 adding and listing machines which, while operating normally to register and print amounts to the full decimal capacity of the keyboard, is adapted for sub-division of printing and accumulating mechanism so as 15 to provide for simultaneously running two or more separate columns or lists of items.

The principal object of the present invention is to arrange in a machine of this 20 particular kind for utilizing one section or subdivision of the accumulating mechanism for keeping count of the number of itemizing operations of the balance of the accumulating mechanism and printing the count simultaneously and along the same horizontal line with the imprint of the total of 25 amount accumulation. In this connection that section of the printing mechanism corresponding with the counting section or subdivision of the accumulating mechanism 30 will be disabled during counting operations, though restored to operativeness for the printing of the count total. When the machine is thus in use for keeping count of the number of itemizing operations means come 35 into play for preventing an overrunning of the amount register section or subdivision of the accumulating mechanism from affecting the section or subdivision of the accumulating mechanism used for counting purposes, 40 the usual transfer devices being disabled at the point of subdivision.

While adapting the machine for such use as above described the invention makes provision for an alternate use whereby two 45 separate columns of imprints can be made, one of amounts being accumulated and the other of dates or designating numbers not accumulated, the section or subdivision of the accumulating mechanism which corresponds 50 with the section or subdivision of the printing mechanism used for date or designating number printing being then utilized to take care of any over-flow from the other section or subdivision of the accumulating mechanism in which amounts are be-

ing registered. In this connection the machine is adapted to print any total thus extended beyond the point of subdivision, the cipher or ciphers being automatically filled in notwithstanding no digit occurs in the total at the first decimal place to the right of the point of sub-division and that during the itemizing there has been a suspension of co-operative action between the impression devices at this point.

The accompanying drawings which form part of this specification illustrate the invention as embodied in an adding and listing machine of the well-known Burroughs type (see William S. Burroughs Patents 60 Nos. 504,963 and 505,078, dated September 12, 1893), but it is to be understood that the invention is not necessarily limited to embodiment in this particular type of machine. Reference may also be had to English Patent 65 No. 656 of 1908 and United States Patent 70 No. 908,430, issued December 29, 1908, on the inventions of J. G. Vincent.

Of said drawings, Figure 1 represents the machine in sectionalized left side elevation 80 with the parts relatively positioned as when the machine is operating under normal conditions; Fig. 2 is a somewhat similar view showing a less number of parts, the latter appearing relatively positioned as when the 85 machine is arranged or adjusted for counting the itemizing operations; Fig. 3 is a somewhat similar view illustrating the effect of depressing the total key when such 90 conditions obtain; Fig. 4 is another sectionalized left side elevation showing the parts relatively positioned, as when the machine is arranged to print two columns and extend the total; Figs. 5 and 6 are vertical sections taken on lines farther to the right than the 95 preceding figures and illustrating the count-controlling devices, Fig. 5 showing the same at normal and Fig. 6 illustrating such parts in action; Fig. 7 is a horizontal section taken on the line 7—7 of Fig. 6; Fig. 8 is a 100 partial front elevation of the machine with some parts in section; Fig. 9 is a section taken substantially on the line 9—9 of Fig. 8; Fig. 10 is a fragmentary sectionalized top plan view taken substantially on the line 105 10—10 of Fig. 1; Figs. 11, 12 and 13 are vertical sectional views of coupling devices in the printing mechanism, Fig. 11 showing the parts at normal, Fig. 12 showing the same under a date or designating number 110

adjustment, and Fig. 13 showing these parts under an extended total adjustment; Fig. 14 is a horizontal section taken on the line 14—14 of Fig. 1; Figs. 15, 16 and 17 show

5 examples of work which can be performed by the machine when equipped with the present invention.

In the drawings, the reference numeral 291 designates the usual depressible amount 10 keys arranged in parallel rows and the keys of each row inscribed from "1" to "9". These keys operate upon small bell cranks 217, to which are coupled stop rods or wires 270 whose laterally turned forward ends 15 slide in slots of fixed upright plates 210 at the front of the machine. The bell cranks as usual operate slip strip or bars 214 which coat with well-known detent devices not necessary to describe or illustrate, and these 20 strips or bars displace the usual latches 415 which normally uphold segmental racks 610 and the front ends of levers 611 with which said racks have the usual slot and pin and spring connection. The levers 611 are 25 loosely mounted on a rock shaft 600 carrying the usual restoring frame or bail 613 and at their rear ends said levers carry segmental series of type plates 618^a adapted to be driven against a roller platen 17 by im- 30 pression hammers 715. The latter coat in the usual way with pivoted hammer drivers 716, normally restrained by pivoted latches 717, the latter adapted to be individually displaced by pivoted pawls 718 held in en- 35 gagement with the latches by springs 780 connecting said pawls with the hammer drivers 716, said springs also constituting the means for firing the hammers. The pawls 718 are as usual carried by a rocking 40 bail and formed with tails to coat with cam shoulder on the levers 611 so the latches will not be individually tripped unless the corresponding levers move far enough to present digital type at the printing line.

45 The numeral 910 designates the left-hand side piece of a rocking frame such as ordinarily employed to support the registering wheels and pinions, and those which in the present instance operated in the ordinary 50 way are designated by the numerals 920, and 916. The numeral 900 designates the pivot shaft of said rocking frame, which shaft extends from side to side of the same, and 958 and 958^a designate studs such as are usually 55 located on the left-hand side piece of this rocking frame above and below said pivot shaft. These studs are adapted as usual to coat with a pitman 914 which is coupled to a three armed lever 913 carrying studs 961 and 961^a which are operated upon by a wipe 60 pawl or plate 821; the latter carried by a rock arm 813. The usual link 911 is coupled to the pitman and through slot and pin connections attached to a bell crank lever 227 65 which is surmounted by the usual total key

265. Said bell crank lever is also connected with a bail 224 adapted to simultaneously withdraw all of the latches 415 when the total key is depressed.

All of the above described parts are familiar in Burroughs adding machines and they operate in the well-known manner.

In carrying out the present invention the stop wire connections for the "1" key of one bank (in this instance the third bank or 75 row from the left) are modified over those usually employed to provide for the counting operation which calls for repeating the single step movement of a wheel or pinion or of the primary one of a set of wheels or 80 pinions. In the present instance the modification in stop wire connections being in the third bank from the left, three wheels are employed to register the count and the primary wheel is of course that one farthest to the right, the same being designated 920^a in Fig. 8 and its pinion 916^a. The bell crank 217^a (Figs. 5 and 6) on which the "1" key above referred to operates does not connect directly with the associated stop wire 270^a 85 but has a one way engagement with an arm z on the same cross-shaft 200 on which said bell crank is loosely mounted, which engagement may be effected by means of a stud z' on the bell crank acting against the front 90 edge of said arm. The stop wire 270^a is connected to said arm, from which it will be obvious that depression of this "1" key will result in retracting said stop wire in the usual way, but it is obvious the stop wire 100 may be retracted by rearward movement of the arm independently of the key bell crank and it is adapted to be so retracted for the purposes of the counting operation. The arm z has at its lower extremity a finger z^2 105 (Fig. 7) projecting laterally to the left behind a plate Z which is mounted to rock loosely upon the aforesaid shaft 200 and act with its rear edge against said finger z^2 to 110 effect the retraction of the stop wire. Said plate is normally held forward and upward by a spiral spring z^3 in an inoperative position as shown in Fig. 5. A spring-held bail 424 similar to that commonly employed in Burroughs machines is constructed and arranged as usual to be swung rearward by any one of the detent strips 214, each of the latter having a downturned lip 214^a bearing against cross rod 402 of this bail. In the present instance the bail has an additional intermediate arm 424^a which, at a point just above the cross rod 402 is formed with a flange z^4 projecting to the right, Fig. 7, and adapted to act against the forward edge of the plate Z, though under normal conditions it passes freely under said plate (see Fig. 5).

Under the lower keyboard plate 212 there is slidably mounted a plate Z' which near its forward end is formed with a downwardly projecting cam portion z^5 adapted 120

when the plate is slid forward to act upon a roller z^6 carried at the upper forward corner of the plate Z , and thereby lower said plate far enough to bring its front edge directly 5 behind the flange z^4 of the bail arm 424^a. The cam portion z^5 of said plate Z' is sufficiently flattened at its apex to preserve the adjustment and it will be seen that depression of any amount key by swinging the 10 bail 424 rearwardly will cause the plate Z to be swung rearwardly, carrying with it the arm z by reason of the engagement between the rear edge of the plate and the finger z^2 of said arm. This retracts the stop 15 wire 270^a as shown in Fig. 6 and provides for a drop of the associated rack 610 the correct distance for registering "1" on the associated number wheel when the rack is returned to normal. It will thus be seen that 20 by sliding the plate Z' forward the machine will be adjusted for registering the count of itemizing operations, it being understood that the count accumulations are carried from the wheel 920^a to the next adjacent 25 wheel 920^b to the left and from the latter to the remaining wheel 920^c through the usual transfer mechanism.

As it is not desirable to print a row of "1s" when the machine is operating under 30 the counting adjustment, special provision is made for disabling the pawl 718 which would ordinarily trip the printing hammer belonging to the third bank from the left. This particular pawl is provided with a stud 35 x , Fig. 2, projecting laterally from its tail portion for coaction with the angular lower edge of one arm of the bell crank lever X pivoted on a cross rod 200^a and carrying at the extremity of its other arm a roller x' . 40 A plate X' is mounted to slide on the under side of the lower keyboard plate 212 and co-operate with said roller, this plate having two downwardly projecting cam portions x^2 x^3 with flattened apexes and a depression 45 between them. A spiral spring x^4 tends to draw the bell crank X forward to effective position but normally the plate X' stands rearward with its forward cam projection x^3 over the roller x' , see Fig. 1, which has 50 the effect of holding the lower end of the bell crank so far rearward and upward as to have no effect upon the pawl 718. When, however, said plate X' is moved part way forward, accompanying the forward movement of the plate Z' before referred to, the depression of said plate X' permits the bell crank lever X to assume the effective position illustrated in Fig. 2, so that in an operation 55 of the machine the pawl 718 will be disabled through coaction between its stud x and the angular lower edge of said lever, as illustrated by dotted lines in Fig. 2. The operating connection between the two plates X' and Z' will be later pointed out, having 60 to do with the operations of a third slide 65

plate with functions besides that of simply operating the two plates X' and Z' .

When a total of the count is to be printed in connection with the total of accumulated amounts, it becomes necessary to displace 70 the bell crank lever X and to this end there is secured to the rock shaft 204 on which the total key bell crank 227 is secured, a rearwardly curved arm X^2 whose rear edge is adapted to act against a roller stud x^5 on 75 said bell crank lever X with the effect illustrated in Fig. 3, where the lower end of said bell crank lever X is shown carried away from the pawl 718, leaving the latter free to trip its latch.

Most of the latches 717 have the usual overlapping tails d , Fig. 14, to provide for the tripping of one latch by another to accomplish the familiar result of filling in ciphers. This automatic action, however, 85 should be suspended, when the counting operation is in progress, between the sections or subdivisions of latches, one of which is associated with the sub-division or section of the printing mechanism which is listing the 90 amounts being accumulated and the other of which is associated with that portion of the printing mechanism used simply to record the total of the count. Hence the third latch to the right designated 717^a does not 95 have one of the overlapping tails d but it is operatively connected with the next adjacent latch to the right by a movable coupling piece A of a similar character to that disclosed in the Gooch Patent No. 825,205, 100 dated July 3, 1906. This coupling piece has at its forward end oppositely projecting offset studs a normally engaging notches in the upper edges of the two latches, so that through the medium of this coupling piece 105 the latch 717^a may trip the adjacent latch to the right, the same as though the usual overlapping tail was present. However, the coupling piece, besides being mounted to slide on a cross rod 706 to accommodate the 110 rocking of the latches, is pivotally movable about said cross rod to uncouple the latches. It will thus be seen that in the printing of totals ciphers between the count total and the amount total may be eliminated, as in 115 the example of work shown by Fig. 16.

A forward extension of the coupler A is connected by a spiral spring a' with an overhead bracket a^2 , said spring thus tending to engage the coupler with the latches. Normally the spring so acts in order to preserve the co-operative relationship between latches. A bail B is pivotally mounted between the side frame pieces above the coupler and the forward cross bar of the bail is adapted to 120 act upon the forward extension of the coupler in opposition to said spring a' , said bail having a forward projection b which is connected to an underlying fixed stud b' by a spiral spring b^2 superior in strength to said 125 130

spring a' . Said bail is, however, normally held up against the stress of said spring b^2 through means hereinafter described.

In the present instance the arrangement 5 is such as to provide for effecting the split or subdivision of the printing mechanism for extended total purposes at a different point from that at which the split is effected for count purposes. In the present instance 10 the printing of dates in the left hand column under an extended total adjustment being contemplated, only two banks of keys need be employed for the left hand column work and the printing mechanism split between 15 the second and third decimal places counting from the left. The second latch 717^b is notched in its upper edge similarly to the third latch 717^a previously described and a coupler A' is employed between these two 20 latches, said coupler being a duplicate of the coupler A as to its rear portion, which has studs a^3 for engaging the latches. This second coupler A' engages the cross rod or shaft 706 in the same manner as does the coupler 25 A, so as to slide thereon when the coupler A' is in engagement with the latches 717^a and 717^b and also adapted to rock on said shaft to disengage from said latches. A spiral spring a^4 connects the forward extension 30 of the coupler A' to the overhead bracket a^2 , said spring normally enforcing engagement of the coupler with the latches. A bail B' overlies the said forward extension of the coupler A' and underlies the before- 35 mentioned bail B and the forward extension of the coupler A, and a spring b^3 connecting said bail B' with the stud b' tends to lower the bail and when free to do so overpowers the spring a^4 , rocking the coupler A' 40 to disengage it from the latches 717^a and 717^b. A vertically disposed bar C is slid- 45 ingly mounted in the frame-work and formed at its lower end with a shouldered portion c engaging under a stud b^4 which projects from the left side of the bail B'. Said bar is upheld by a spiral spring C', Fig. 1, of sufficient strength to overcome both the spring b^2 and the spring b^3 . The upper bail B has a lip b^5 , Fig. 14, projecting 50 from the left side and overlying a portion of the bail B'. The bar C normally upholds the bail B' with its front cross bar spaced from the forward extension of the coupler A' as shown in Fig. 11, and also upholds 55 the bail B by reason of the engagement between the lip b^4 of the latter and the under-lying bail B'. Hence the springs a' and a^4 are free to normally enforce engagement between both couplers A and A' and their 60 latches.

A strip or bar C² is suitably mounted to slide on the under side of the lower keyboard plate 212, Fig. 4, and at its rear end has an irregular formation providing 65 stepped shoulders c' c^2 with cam surfaces

leading to them. The bar C carries at its upper end a roller c^3 for coacting with this irregular portion of the slide strip or bar C². Normally, as shown by dotted lines in Fig. 1, said roller bears against a plain portion of the strip to the rear of the irregularly formed portion, the said strip being then in its foremost position. When the strip is slid rearward one step its cam surface just in rear of the step c' acts upon the roller c^3 and thrusts the bar C downward, the roller coming to rest upon said shoulder. This downward movement of the bail is sufficient to permit lowering of the upper bail B to the position shown in Fig. 12, said bail displacing the coupler A. The lower bail B' moves downward also but not far enough to act upon the other coupler A'. Movement of the slide strip C² another step to the rear causes its cam surface just in rear of the shoulder c^2 to act upon the roller c^3 and thrust the bar C farther downward, said roller coming to rest on said shoulder, as shown in Fig. 4. This further downward movement of the bar C permits further lowering of the bail B' as illustrated in Fig. 13, said bail then acting to displace the coupler A'. When this takes place the other coupler A should be restored to normal position and to this end there is loosely mounted upon the cross rod or shaft 706 a cam plate D which is adapted to act upon a down-turned cam flange b^6 of the upper bail B. Said cam plate is formed on the upper side of said cross rod or shaft, with a nose to act upon said cam flange and on the forward side of said cross rod or shaft with a finger b^7 to be acted upon by the lower bail B'. It results that when said bail B' is lowered far enough to displace the coupler A' it rocks the cam plate, causing the latter to lift the bail B, the spring b^3 being superior to the spring b^2 . The slide strip C² is operatively connected to the beforementioned slide strips Z' X' by levers z^6 and x^6 pivoted intermediate their ends upon the upper side of the lower keyboard plate 212 and having slot and pin connections at opposite ends with the slide strips, the pins extending through slots in 110 said keyboard plate. The slide strip C² has at its forward end a post c^4 projecting through slots in the keyboard plates, and surmounted by a knob or finger piece C³ above an index plate C⁴ secured on the keyboard as shown in Fig. 10 and slotted to accommodate the post c^4 . The said knob has an index finger c^5 adapted to register with any one of three inscriptions on the plate, such inscriptions in the present instance being an abbreviation of the word "normal," to-wit "Norl," the word "Count" and the word "Date." Movement of the knob to bring its pointer c^5 opposite the word "Count" carries the strip C² one step rear- 125 130

ward with the effect on the coupling devices already described. This movement of said strip is accompanied by forward movement of the strips Z' and X' with other results 5 already described, to-wit the rocking of the cam plate Z so that the stop rod or wire 270^a will come into action for count purposes, and the rocking of the lever X to effective position for disabling a section of the printing mechanism.

It has been before stated that the racks 610 have the usual slot-and-pin connection with the levers 611. These racks are as usual 10 spring-drawn in upward direction for the purpose of carrying as in the ordinary Burroughs machine and they are normally restrained from movement under the impulse of the springs by the usual transfer pawls 413. The racks coöperate severally with 15 pinions 916, 916^a, 916^b and 916^c, and the latter have the usual transfer projections for tripping the pawls 413. In the present instance, however, the pinions do not all remain at all times axially aligned as in previous machines. They do so remain as long 20 as the knob C^3 is not moved to the "Date" position but when the knob is moved to the latter position the two pinions 916^b and 916^c and the number wheels 920^b and 920^c carried 25 by them, which belong to the two left-hand rows of keys, may remain out of engagement with the racks 610 while the remaining pinions move into engagement with their racks. Thus the racks to the left of the split 30 may return to normal without affecting their pinions and the only movement imparted to the pinions will be that which takes place by reason of the over-running of the pinions to the right of the split. Thus it will be obvious 35 that a total to the right of the split can be extended to the left of the split.

Now the two left-hand pinions and their number wheels are carried in an inner frame movable about the shaft 900 independently 40 of the main frame of which the side plate 910 is a part. This main frame as usual comprises intermediate plates 910^a besides a right-hand plate similar to the left-hand plate 910, and also a tie rod 910^b. The 45 wheels and pinions to the right of the split are separately mounted as usual between pairs of plates 910^a. Plates 920 somewhat similar to the usual plates 910^a are used to the left of the split but are slotted at e 50 where they embrace the tie-rod 910^b. These special plates 920 of which there are four 55 make up the inner frame before mentioned, together with short tie-rods 920^c which connect the plates. The frame thus composed 60 supports in its upper portion the two left-hand pinions and number wheels independently mounted for rotation in much the same way as the balance of the pinions and wheels. It will be noted that this inner frame may 65 rock on the shaft 900 independently of the

main frame an extent determined by the length of the slots e . This is sufficient to provide for disengagement of the two left-hand pinions from their racks while the remaining pinions are engaged with their 70 racks. The left-hand side plate 920 of the inner frame has a forwardly and downwardly extending arm 920^c which carries a screw stud f at its extremity. On this stud are loosely mounted a pair of latches F and F' , 75 each separately drawn downward by springs f' and f^2 , tending to engage the latches over the rear of the stud 958, which is elongated for the purpose. When either of these latches is engaged with that stud the inner 80 frame is locked to the main frame and will operate as though a part of it. The left-hand latch F' is normally disengaged from said stud by reason of the fact that the upper edge of the pitman 914 just in rear of its 85 notch abuts the under-edge of the latch as shown in Figs. 1 and 4, but the right-hand latch F is normally engaged with the stud and remains so as long as the knob C^3 is not moved to the "Date" adjustment. The strip 90 C^2 which is slid back and forth by the said knob has at an intermediate point a cam-rise f^4 . When the strip is moved beyond the "Count" adjustment, that is to say when the knob is moved to the "Date" position, this 95 cam-rise of the strip acts upon a roller f^5 carried in the rear end of an arm F^2 secured to the rock-shaft 200 and extending in rear thereof. The depression of this arm by the rearward movement of the strip rocks the 100 shaft and elevates an arm F^3 secured to the latter and projecting forwardly. This arm F^3 is connected by a dependent link F^4 with the latch F , said link being hooked under a stud on said latch as shown at f^6 in Figs. 1 105 and 4. A spring F^5 draws downwardly upon the arm F^3 permitting the latch F to maintain its engagement with the stud 958 so long as the knob C^3 is not moved to the "Date" position. 110

With the knob at the "Date" adjustment and the inner frame unlatched from the regular accumulator frame, in an itemizing operation both frames will be swung forward in the usual way, the tie-rod 910^b carrying the inner frame along with the outer frame. However, the inner frame will not 115 be returned with the outer frame, not being latched thereto and hence the two left-hand racks in rising will have no effect upon the 120 pinions in this inner frame. It will thus be seen that so long as the inner frame is unlatched there can be no accumulation of amounts on the wheels in that frame as a result of the depression of keys in the two 125 left-hand banks. However, it is of course necessary in order to secure the extended total that these two left-hand wheels shall return to mesh with their racks in time to take transfers from the wheels to the right 130

and from one to the other. Therefore, means are provided for rocking the inner frame just as the handle reaches the end of its return stroke and immediately after the return stroke 5 the storing bail 613 has reached its home position. The left hand plate 920 of the inner frame is extended downward as clearly shown in Fig. 4 and there is jointed to it a link 920^a which at its rear end is curved and slotted as shown at *g* to engage a stud *g'* on the rocking arm 813. This last-mentioned figure of the drawings illustrates the relation of parts under a "Date" adjustment just as the handle is about to finish its return stroke 10 and the stud *g'* is about to strike the right-hand end of the slot *g*. Its action against that end of the slot is sufficient to thrust the link 920^a far enough to rock the inner frame and engage its pinions with the racks. Then it will be obvious that if the adjacent wheel 15 of the regular set has tripped its transfer pawl the carrying movement will take effect upon the right-hand one of the two wheels in the inner frame and if that movement im- 20 parting to such wheel carries it past the nine position then it will in turn trip the transfer pawl associated with it and cause a carrying movement to take place in the other wheel in the inner frame. 25

As the extended total wheels may be out of mesh at the time the transfer pawl is tripped by the adjacent wheel of the regular set, it is necessary to provide means for preventing the transfer or carrying movement 30 of the rack for the right-hand one of the extended total wheels, until that wheel comes into mesh with the rack. Such means are illustrated in Figs. 1, 4 and 9, and it will be observed that there is swung from the same 35 stud that supports the transfer pawl 413 another pawl 413^a having a finger *h* separated from its main portion a little more than the diameter of the usual stud 414 on the rack which co-operates with the regular transfer 40 pawl. This finger *h* normally stands in rear of that stud as shown in Fig. 1 so that it does not obstruct the same. This auxiliary transfer pawl is drawn forward by a spring *i* but is normally held rearward by the inner 45 accumulator frame, one of whose plates 920 is formed with a rearwardly and upwardly projecting arm *h'* having a forwardly-turned upper end portion with a laterally projecting flange *h*² standing in front of the 50 lower rounded extremity *h*³ of the auxiliary transfer pawl as clearly illustrated in Fig. 9. When the inner frame rocks forward the auxiliary transfer pawl follows it by reason of the action of the spring *i* and the finger *h* 55 is then brought to position over the stud 414 as illustrated in Fig. 4. The rocking back of the regular frame of course has no effect upon this auxiliary pawl. It continues to restrain the rack until the inner frame rocks back and its pinions are engaged with its

racks. Then the restrained rack is released by the auxiliary pawl and the transfer may take place. To prevent the inner frame from accidentally returning to mesh with the racks its weight is supplemented by a spring *j* tending to hold the frame in its outer position, said spring being attached to a forwardly projecting arm of one of the plates 920 and to a fixture on the lower part of the regular side plate 910. 75

In order to print the extended total it will be understood that all the hammer driver latches should be co-operatively related. Of course during the itemizing under the "Date" adjustment the split is effective. 80 This means of course that the coupler A' is raised out of engagement with the second and third latches counting from the left. When an extended total is to be taken this coupler should be restored as of course the accumulator wheels to the left of the split come into play. To this end means are provided whereby the depression of the total key will result in restoring said coupler to operative position. To this end the bail B' 90 is formed with an angular rearward extension B² which extends under a roll *m* on the rear end of a curved lever M whose upwardly extending arm has pivotally connected with it a link M' (Figs. 1 and 14) longitudinally 95 slotted to embrace a stud *m*² upon a rearward projection of the vertical bar C. The link has an upstanding rear portion carrying a stud *m*³. A spring *m*⁴ attached to the link M' tends to draw the same forward and 100 therefore elevate the rearwardly-extending arm of the lever M and prevent it from affecting the bail B'. The bell crank lever 227 on which the total key is mounted is connected by a link 226 (Fig. 1) with an arm 105 227^a depending from and secured to a rock-shaft 206, and the latter has secured to it another depending arm N bent over and doubled back at its lower extremity (see Fig. 14) forming a foot *n* adapted to operate 110 upon this stud *m*³ under certain conditions. It will be noted that the position of the link M' is determined by the adjustment of the bar C and the latter is of course determined by the manipulation of the knob C³. While 115 the knob remains either at "Normal" or at "Count" adjustment the bar C is not lowered far enough to bring the said stud *m*³ in line with the foot *n* (see Figs. 1 and 2). Consequently in the taking of a total no effect is 120 produced upon the bail B' by depression of the total key. However, when the knob C³ is moved to the "Date" position the shoulder *c*² of the irregular portion of the strip C² rides over the roll *c*³ on the bar C and further depresses the latter. This brings the stud *m*³ in line with the foot *n*. Consequently when the total key is depressed said foot acts on the stud and draws the link M' rearwardly, 125 rocking the lever M and raising the bail B' 130

by pressure of the roll m upon the forward extension of said bail. This permits the coupler A' to become engaged with the notched latches 717^a and 717^b . Hence the 5 tripping from right to left throughout the entire series of latches takes place.

Of course it will be understood that in order to obtain the extended total all the pinions must remain in engagement with 10 their racks during the forward stroke of the operating handle. Now the spring j as well as the weight of the inner accumulator frame and its two pinions and wheels will tend to disengage these pinions from their 15 racks as the arm 813 starts rearward relieving the link 920^a of the restraint imposed upon it by the stud g' . It is in this connection that the latch F' comes into play. It will be recalled that this latch is normally 20 upheld by the pitman 914 so as not to engage the stud 958 (Figs. 1 and 4). When the pitman is lowered by depression of the total key said latch F' drops behind the said stud 958 and thus prevents the disengagement of 25 the two pinions from their racks. All of the accumulating pinions move out of mesh with their racks at the beginning of the rear or return stroke of the operating handle as usual in the taking of a grand total on a 30 regular Burroughs machine. Of course at the conclusion of the operation the pitman 914 rises to its normal position and lifts the latch F' but the inner accumulator frame has meantime been rocked through the 35 medium of the link 920^a so as to engage the two extended total pinions with their racks at the same time that the balance of the pinions are returned to engagement with the racks through the usual means, comprising a 40 rearwardly projecting arm 919 secured to the rock shaft 900 near its right-hand end and having a cam edge acted upon by a roller 311^a on the full stroke sector 311 , all as illustrated in Fig. 1.

45 The usual form of locking means is employed to prevent turning of the pinions when disengaged from their racks, said locking means comprising a frame journaled on the shaft 900 and composed of side plates 50 926 , intermediate plates 926^a with locking noses, and cross rods 926^b . Said frame cooperates with the usual locking lever such as illustrated in Burroughs' Patent No. 504,963. It will be understood that whenever the 55 accumulator wheels to the right of the split move out of mesh with their racks the wheels to the left of the split must necessarily be moved out of mesh with their racks also and to just the same extent, by 60 reason of the engagement of the tie-rod 910^b against the front ends of the slots e . Consequently the extended total pinions are locked against turning just the same as though they were mounted in the ordinary

way and not in a support capable of independent movement.

It will be understood that when the knob C^3 is moved to the "Date" position the resultant forward movement of the slide strip Z' will carry its cam portion z^5 forwardly 70 beyond the roller z^6 , so as to disable the "Count" devices, and likewise the forward movement of the slide strip X' will cause its second cam portion x^2 , Fig. 2, to act on the roller x' to disable the lever X .

In order to guard against a possible miscount of operations when the machine is adjusted for utilization of the three left-hand wheels for counting purposes, by reason of transfer actuation of the right-hand one of 80 those three wheels, means are provided for disabling the transfer mechanism between such right-hand wheel and the left-hand wheel of the regular set, whenever the machine is adjusted for counting purposes. 85 Thus, the rack belonging to the pinion of said right-hand counting wheel is prevented from partaking of extra movement, notwithstanding the regular pawl restraining that rack may be displaced by the transfer projection of the left-hand pinion of the regular set and said pawl latched in its displaced position in the regular way. Referring to Fig. 9, the reference numeral 413^c designates an auxiliary pawl mounted upon 90 the same pivot stud that supports the regular pawl 413 , said auxiliary pawl having a finger w adapted to engage over the stud 414 of the rack belonging to the right-hand counting wheel. Under a normal adjustment of the machine this finger stands in rear of said stud, as illustrated by the position of pawl 413^a in Fig. 1, though a spiral spring w' attached to the auxiliary pawl tends to draw said finger over the stud to 100 the position shown in Fig. 9. The pawl has an angular arm w^2 extending above its pivot and presenting a rear edge w^3 to a roller w^4 on the depending arm w^6 of a bell crank lever having a forwardly projecting 110 arm w^6 carrying a roller w^7 adapted to co-operate with a cam portion w^8 of the slide strip C^2 . A spring w^9 draws the bell crank arm w^5 forward and, being superior to the spring w' or acting on the auxiliary pawl 115 through greater leverage, normally holds the lower arm of the pawl rearward, so that the finger w will not obstruct the stud 414, but the latter may pass into a notch w^{10} of the auxiliary pawl. Normally the roller w^7 lies 120 against a plain portion of the strip C^2 , but when said strip is moved rearward to the "Count" position, as shown in Fig. 9, the cam w^8 acts upon said roller, rocking the bell crank and permitting spring w' to draw 125 the finger w over the stud 414. The apex of the cam portion w^8 is flattened for the purpose of preserving the adjustment, but

when the strip is moved farther rearward to the "Date" position said cam portion is carried in rear of the roller *w* so that the finger *w* will be again moved to the rear of 5 the stud 414 and the transfer mechanism be permitted to act as usual.

What is claimed is:

1. In a machine of the class described, the combination of reciprocating racks; type-carriers movable therewith; axially-aligned pinions actuated by the racks; impression devices coacting with the type and co-operatively related for cipher-printing with provisions for interrupting and restoring at 15 will the co-operative relationship at a predetermined point; and means effecting coaction between the rack and its pinion to one side of such point to automatically accumulate a count of operations of pinions to the 20 other side of such point as an incident to such operations.

2. In a machine of the class described, the combination of reciprocating racks; setting-up devices for regulating the degree 25 of movement of said racks; type-carriers movable therewith; axially-aligned pinions actuated by the racks; impression devices coacting with the type and co-operatively related for cipher-printing with provisions 30 for interrupting and restoring at will the co-operative relationship at a predetermined point; and means, controlled by the setting devices, for effecting coaction between a rack and its pinion to one side of such point 35 to automatically accumulate a count of operations of pinions to the other side of such point as an incident to such operations.

3. In a machine of the class described, the combination of reciprocating racks; setting-up devices for regulating the degree of 40 movement of said racks; type-carriers movable therewith; axially-aligned pinions actuated by the racks; impression devices coacting with the type and co-operatively related for cipher-printing with provisions 45 for interrupting and restoring at will the co-operative relationship at a predetermined point; manipulative means for controlling such provisions; and means, controlled by 50 said manipulative means and by the setting-up devices, for effecting coaction between a rack and its pinion to one side of such point to automatically accumulate a count of operations of pinions to the other side of such point as an incident to such operations.

4. In a machine of the class described, the combination of reciprocating racks; type-carriers movable therewith; axially aligned pinions actuated by the racks; impression 60 devices coacting with the type and co-operatively related for cipher-printing with provisions for interrupting and restoring at will the co-operative relationship at a predetermined point; means for effecting coaction between a rack and its pinion to one 65

side of such point to automatically accumulate a count of operations of pinions to the other side of such point as an incident to such operations, and means for preventing impression actuation of type set in the 70 counting operation.

5. In a machine of the class described, the combination of reciprocating racks; type-carriers movable therewith; axially-aligned pinions actuated by the racks; impression 75 devices coacting with the type and co-operatively related for cipher-printing with provisions for interrupting and restoring at will the co-operative relationship at a predetermined point; manipulative means for 80 controlling such provisions; means, controlled by said manipulative means, for effecting coaction between a rack and its pinion to one side of such point to automatically accumulate a count of operations 85 of pinions to the other side of such point as an incident to such operations, and means, also controlled by said manipulative means, for preventing impression actuation of the type set in the counting op- 90 eration.

6. In a machine of the class described, the combination of reciprocating racks; setting-up devices for regulating the degree of 95 movement of said racks; type-carriers movable therewith; axially-aligned pinions actuated by the racks; impression devices coacting with the type and co-operatively related for cipher-printing with provisions 100 for interrupting and restoring at will the co-operative relationship at a predetermined point; manipulative means for controlling such provisions; means, controlled by said manipulative means and by the setting-up devices, for effecting coaction between a 105 rack and its pinion to one side of such point to automatically accumulate a count of operations of pinions to the other side of such point as an incident to such operations, and means, also controlled by said manipulative 110 means, for preventing impression actuation of type set in the counting operation.

7. In a machine of the class described, the combination of reciprocating racks; type-carriers movable therewith; axially aligned pinions actuated by the racks; impression devices coacting with the type and co-operatively related for cipher-printing with provisions for interrupting and restoring at 115 will the co-operative relationship at a predetermined point; means for effecting coaction between a rack and its pinion to one side of such point to automatically accumulate a count of operations of pinions to the other side of such point as an incident to such operations, and means for causing backward turning of pinions to set up type on both sides of such point of interruption.

8. In a machine of the class described, the combination of reciprocating racks; type- 120

carriers movable therewith; axially alined pinions actuated by the racks; impression devices coacting with the type and coöperatively related for cipher-printing with provisions

- 5 for interrupting and restoring at will the coöperative relationship at a predetermined point; means for effecting coaction between a rack and its pinion to one side of such point to automatically accumulate a count of operations of pinions to the other side of such point as an incident to such operations, means for preventing impression actuation of type set in the counting operation; and means for causing backward turning of pinions to set up type on both sides of such point of interruption, with provisions for disabling the aforesaid means for preventing impression actuation.

9. In a machine of the class described, the combination of reciprocating racks; setting-up devices for regulating the degree of movement of said racks; type-carriers movable therewith; axially-alined pinions actuated by the racks; impression devices coacting with the type and coöperatively related for cipher-printing with provisions for interrupting and restoring at will the coöperative relationship at a predetermined point; manipulative means for controlling such provisions; means, controlled by said manipulative means and by the setting-up devices, for effecting coaction between a rack and its pinion to one side of such point to automatically accumulate a count of operations of pinions to the other side of such point as an incident to such operations, means, also controlled by said manipulative means, for preventing impression actuation of type set in the counting operation; and means for causing backward turning of pinions to set up type on both sides of such point of interruption, with provisions for disabling the aforesaid means for preventing impression actuation.

45 10. In a machine of the class described, the combination of reciprocating racks; type-carriers movable therewith; axially alined pinions actuated by the racks; impression devices coacting with the type and coöperatively related for cipher-printing with provisions for interrupting and restoring at will the coöperative relationship at a predetermined point; means for effecting coaction between a rack and its pinion to one side of such point to automatically accumulate a count of operations of pinions to the other side of such point as an incident to such operations, and means capable of varied manipulation to effect interruption in coöperative action of impression devices with or without bringing into play said counting means.

55 11. In a machine of the class described, the combination of reciprocating racks; type-carriers movable therewith; axially

aligned pinions actuated by the racks; impression devices coacting with the type and coöperatively related for cipher-printing with provisions for interrupting and restoring at will the coöperative relationship at 70 either of two predetermined points; means for effecting coaction between a rack and its pinion to one side of such point to automatically accumulate a count of operations of pinions to the other side of such point as 75 an incident to such operations, and means capable of varied manipulation to effect interruption of coöperative action of impression devices at that point and bring into play the counting means or to effect the interruption at the other point without bringing such means into play.

12. In a machine of the class described, the combination of reciprocating racks; type-carriers movable therewith; axially 85 aligned pinions actuated by the racks; impression devices coacting with the type and coöperatively related for cipher-printing with provisions for interrupting and restoring at will the coöperative relationship at a 90 predetermined point; means for effecting coaction between a rack and its pinion to one side of such point to automatically accumulate a count of operations of pinions to the other side of such point as an incident to 95 such operations, means capable of varied manipulation to effect interruption in coöperative action of impression devices with or without bringing into play said counting means; and means controlled by said manipulative means for preventing impression actuation of type set in a counting operation.

13. In a machine of the class described, the combination of reciprocating racks; setting-up devices for regulating the degree of 105 movement of said racks; type-carriers movable therewith; axially-alined pinions actuated by the racks; impression devices coacting with the type and coöperatively related for cipher-printing with provisions for interrupting and restoring at will the coöperative relationship at a predetermined point; means, controlled by the setting devices, for effecting coaction between a rack and its pinion to one side of such point to 110 automatically accumulate a count of operations of pinions to the other side of such point as an incident to such operations, and means capable of varied manipulation to effect interruption in coöperative action of 115 impression devices with or without bringing into play said counting means.

14. In a machine of the class described, the combination of reciprocating racks; setting-up devices for regulating the degree of 125 movement of said racks; type-carriers movable therewith; axially-alined pinions actuated by the racks; impression devices coacting with the type and coöperatively related for cipher-printing with provisions for in- 120

terrupting and restoring at will the coöperative relationship at a predetermined point; means, controlled by the setting devices, for effecting coaction between a rack and its pinion to one side of such point to automatically accumulate a count of operations of pinions to the other side of such point as an incident to such operations, means capable of varied manipulation to effect interruption in coöperative action of impression devices with or without bringing into play said counting means; and means controlled by said manipulative means for preventing impression-actuation of type set in a counting operation.

15. In a machine of the class described, the combination of reciprocating racks; setting-up devices for regulating the degree of movement of said racks; type-carriers movable therewith; axially-aligned pinions actuated by the racks; impression devices coacting with the type and coöperatively related for cipher-printing with provisions for interrupting and restoring at will the coöperative relationship at either of two predetermined points; means controlled by the setting-up devices for effecting coaction between a rack and its pinion to one side of such point to automatically accumulate a count of operations of pinions to the other side of such point as an incident to such operations, and means capable of varied manipulation to effect interruption of coöperative action of impression devices at that point and bring into play the counting means or to effect the interruption at the other point without bringing such means into play.

16. In a machine of the class described, the combination of reciprocating racks; type-carriers movable therewith; axially aligned pinions actuated by the racks; impression devices coacting with the type and coöperatively related for cipher-printing with provisions for interrupting and restoring at will the coöperative relationship at either of two predetermined points; means for effecting coaction between a rack and its pinion to one side of such point to automatically accumulate a count of operations of pinions to the other side of such point as an incident to such operations, means capable of varied manipulation to effect interruption of coöperative action of impression devices at that point and bring into play the counting means or to effect the interruption at the other point without bringing such means into play; and means controlled by said manipulative means for preventing impression-actuation of type set in a counting operation.

17. In a machine of the class described, the combination of reciprocating racks; setting-up devices for regulating the degree of

movement of said racks; type-carriers movable therewith; axially-aligned pinions actuated by the racks; impression devices coacting with the type and coöperatively related for cipher-printing with provisions for interrupting and restoring at will the coöperative relationship at either of two predetermined points; means controlled by the setting-up devices for effecting coaction between a rack and its pinion to one side of such point to automatically accumulate a count of operations of pinions to the other side of such point as an incident to such operations, means capable of varied manipulation to effect interruption of coöperative action of impression devices at that point and bring into play the counting means or to effect the interruption at the other point without bringing such means into play; and means controlled by said manipulative means for preventing impression-actuation of type set in a counting operation.

18. In a machine of the class described, the combination of reciprocating racks; type-carriers movable therewith; axially aligned pinions actuated by the racks; impression devices coacting with the type and coöperatively related for cipher-printing with provisions for interrupting and restoring at will the coöperative relationship at a predetermined point; means for effecting coaction between a rack and its pinion to one side of such point to automatically accumulate a count of operations of pinions to the other side of such point as an incident to such operations, means capable of varied manipulation to effect interruption in coöperative action of impression devices with or without bringing into play said counting means; and means for causing backward turning of pinions to set up type on both sides of such point of interruption.

19. In a machine of the class described, the combination of reciprocating racks; type-carriers movable therewith; axially aligned pinions actuated by the racks; impression devices coacting with the type and coöperatively related for cipher-printing with provisions for interrupting and restoring at will the coöperative relationship at a predetermined point; means for effecting coaction between a rack and its pinion to one side of such point to automatically accumulate a count of operations of pinions to the other side of such point as an incident to such operations, means capable of varied manipulation to effect interruption in coöperative action of impression devices with or without bringing into play said counting means; means controlled by said manipulative means for preventing impression-actuation of type set in a counting operation; and means for causing backward turning of pinions to set up type on both sides

of such point of interruption, with provisions for disabling the aforesaid means for preventing impression actuation.

20. In a machine of the class described, 5 the combination of reciprocating racks; type-carriers movable therewith; axially aligned pinions actuated by the racks; impression devices coacting with the type and cooperatively related for cipher-printing 10 with provisions for interrupting and restoring at will the coöperative relationship at either of two predetermined points; means for effecting coaction between a rack and its pinion to one side of such point to 15 automatically accumulate a count of operations of pinions to the other side of such point as an incident to such operations, means capable of varied manipulation to effect interruption of coöperative action of 20 impression at that point and bring into play the counting means or to effect the interruption at the other point without bringing such means into play; and means for causing backward turning of pinions to set up 25 total type on both sides of either of the points of interruption.

21. In a machine of the class described, the combination of reciprocating racks; setting-up devices for regulating the degree 30 of movement of said racks; type-carriers movable therewith; axially-aligned pinions actuated by the racks; impression devices coacting with the type and coöperatively related for cipher-printing with provisions 35 for interrupting and restoring at will the coöperative relationship at either of two predetermined points; means controlled by the setting-up devices for effecting coaction between a rack and its pinion to one side of 40 such point to automatically accumulate a count of operations of pinions to the other side of such point as an incident to such operations, means capable of varied manipulation to effect interruption of coöperative action of impression devices at that point and bring into play the counting means or to effect the interruption at the other point without bringing such means into play; means controlled by said manipulative 45 means for preventing impression actuation of type set in a counting operation; and means for causing backward turning of pinions to set up total type on both sides of either of the points of interruption with 50 provisions for disabling the aforesaid means for preventing impression-actuation.

22. In a machine of the class described, the combination of reciprocating racks; type-carriers movable therewith; axially 55 aligned pinions actuated by the racks; impression devices coacting with the type and coöperatively related for cipher-printing with provisions for interrupting and restoring at will the coöperative relationship at a predetermined point; means for effecting

coaction between a rack and its pinion to one side of such point to automatically accumulate a count of operations of pinions to the other side of such point as an incident to such operations, transfer or carrying mechanism for the entire series of pinions; and means for disabling such mechanism between pinions on opposite sides of the said point of interruption. 70

23. In a machine of the class described, 75 the combination of reciprocating racks; setting-up devices for regulating the degree of movement of said racks; type-carriers movable therewith; axially-aligned pinions actuated by the racks; impression devices 80 coacting with the type and coöperatively related for cipher-printing with provisions for interrupting and restoring at will the coöperative relationship at a predetermined point; manipulative means for controlling 85 such provisions; means, controlled by said manipulative means and by the setting-up devices, for effecting coaction between a rack and its pinion to one side of such point to automatically accumulate a count of operations of pinions to the other side of such point 90 as an incident to such operations, transfer or carrying mechanism for the entire series of pinions; and means controlled by said manipulative means for disabling 95 said transfer mechanism between pinions on opposite sides of said point of interruption.

24. In a machine of the class described, 100 the combination of reciprocating racks; type-carriers movable therewith; axially-aligned pinions actuated by the racks; impression devices coacting with the type and coöperatively related for cipher-printing with provisions for interrupting and restoring at will the coöperative relationship at a predetermined point; manipulation means for controlling such provisions; means, controlled by said manipulative means, for effecting coaction between a rack and its pinion to one side of such point to 105 automatically accumulate a count of operations of pinions to the other side of such point as an incident to such operations, means, also controlled by said manipulative means, for preventing impression actuation of the type set in the counting operation; transfer or carrying mechanism for the entire series of pinions; and means controlled by said manipulative means for disabling 110 said transfer mechanism between pinions on opposite sides of said point of interruption. 115

25. In a machine of the class described, 120 the combination of reciprocating racks; type-carriers movable therewith; axially-aligned pinions actuated by the racks; impression devices coacting with the type and coöperatively related for cipher-printing with provisions for interrupting and restoring at will the coöperative relationship at a predetermined point; means for effecting 125

coaction between a rack and its pinion to one side of such point to automatically accumulate a count of operations of pinions to the other side of such point as an incident to 5 such operations, means capable of varied manipulation to effect interruption in co-operative action of impression devices with or without bringing into play said counting means; transfer or carrying mechanism for 10 the entire series of pinions; and means controlled by said manipulative means for disabling said transfer mechanism between pinions on opposite sides of said point of interruption when the counting means is brought 15 into play.

26. In a machine of the class described, the combination of reciprocating racks; type-carriers movable therewith; axially alined pinions actuated by the racks; im- 20 pression devices coacting with the type and coöperatively related for cipher-printing with provisions for interrupting and restoring at will the coöperative relationship at either of two predetermined points; means for effecting 25 coaction between a rack and its pinion to one side of such point to automatically accumulate a count of operations of pinions to the other side of such point as an incident to such operations; means capable of varied 30 manipulation to effect interruption of co-operative action of impression devices at that point and bring into play the counting means or to effect the interruption at the other point without bringing such means 35 into play; transfer or carrying mechanism for the entire series of pinions; and means controlled by said manipulative means for disabling said transfer mechanism between pinions on opposite sides of said point of 40 interruption when the counting means is brought into play.

27. In a machine of the class described, the combination of reciprocating racks; type-carriers movable therewith; axially 45 alined pinions actuated by the racks; im- pression devices coacting with the type and coöperatively related for cipher-printing with provisions for interrupting and restoring at will the coöperative relationship at a 50 predetermined point; means for effecting coaction between a rack and its pinion to one side of such point to automatically accumulate a count of operations of pinions to the other side of such point as an incident to 55 such operations; means capable of varied manipulation to effect interruption in co-operative action of impression devices with or without bringing into play said counting means; and means for preventing accumu- 60 lative coöperation between pinions and racks to one side of such point of interruption, when the counting means is not brought into play.

28. In a machine of the class described, 65 the combination of reciprocating racks;

type-carriers movable therewith; axially alined pinions actuated by the racks; im- pression devices coacting with the type and coöperatively related for cipher-printing with provisions for interrupting and restoring 70 at will the coöperative relationship at a predetermined point; means for effecting coaction between a rack and its pinion to one side of such point to automatically accumulate a count of operations of pinions to the 75 other side of such point as an incident to such operations; means capable of varied manipulation to effect interruption in co-operative action of impression devices with or without bringing into play said counting 80 means; and means for preventing accumulative coöperation between pinions and racks to one side of such point of interruption, when the counting means is not brought into play, while preserving coöperative relation- 85 ship for transfer purposes.

29. In a machine of the class described, the combination of reciprocating racks; type-carriers movable therewith; axially alined pinions actuated by the racks; im- 90 pression devices coacting with the type and coöperatively related for cipher-printing with provisions for interrupting and restoring at will the coöperative relationship at either of two predetermined points; means for effecting 95 coaction between a rack and its pinion to one side of such point to automatically accumulate a count of operations of pinions to the other side of such point as an incident to such operations; means 100 capable of varied manipulation to effect interruption of coöperative action of impres- sion at that point and bring into play the counting means or to effect the interruption at the other point without bringing such 105 means into play; and means for preventing accumulative coöperation between pinions and racks to one side of said latter point.

30. In a machine of the class described, the combination of reciprocating racks; 110 type-carriers movable therewith; axially alined pinions actuated by the racks; im- pression devices coacting with the type and coöperatively related for cipher-printing with provisions for interrupting and restoring 115 at will the coöperative relationship at either of two predetermined points; means for effecting coaction between a rack and its pinion to one side of such point to automatically accumulate a count of operations of pinions to the other side of such point as an incident to such operations; means capable of varied manipulation to effect interruption of coöperative action of impression devices at that point and bring into play the 120 counting means or to effect the interruption at the other point without bringing such means into play; and means for preventing accumulative coöperation between pinions and racks to one side of said latter point, 125

130

while preserving coöperative relationship for transfer purposes.

31. In a machine of the class described, the combination of reciprocating racks; 5 type-carriers movable therewith; axially alined pinions actuated by the racks; impression devices coacting with the type and coöperatively related for cipher-printing with provisions for interrupting and restoring at will the coöperative relationship at a predetermined point; means for effecting coaction between a rack and its pinion to one side of such point to automatically accumulate a count of operations of pinions 10 to the other side of such point as an incident to such operations; means capable of varied manipulation to effect interruption in coöperative action of impression devices with or without bringing into play 15 said counting means; means controlled by said manipulative means for preventing impression-actuation of type set in a counting operation; and means for preventing accumulative coöperation between pinions and 20 racks to one side of such point of interruption, when the counting means is not brought into play.

32. In a machine of the class described, the combination of reciprocating racks; type-carriers movable therewith; axially alined pinions actuated by the racks; impression devices coacting with the type and coöperatively related for cipher-printing with provisions for interrupting and restoring at will the coöperative relationship at a predetermined point; means for effecting coaction between a rack and its pinion to one side of such point to automatically accumulate a count of operations of pinions to the other side of such point as an incident to such operations, means capable of varied manipulation to effect interruption in coöperative action of impression devices with or without bringing into play said counting means; means controlled by said manipulative means for preventing impression-actuation of type set in a counting operation; and means for preventing accumulative coöperation between pinions and racks to one side 35 of such point of interruption, when the counting means is not brought into play, while preserving coöperative relationship for transfer purposes.

33. In a machine of the class described, the combination of reciprocating racks; setting-up devices for regulating the degree of movement of said racks; type-carriers movable therewith; axially alined pinions actuated by the racks; impression devices coacting with the type and coöperatively related for cipher-printing with provisions for interrupting and restoring at will the coöperative relationship at either of two predetermined points; means controlled by the setting-up devices for effecting coaction be-

tween a rack and its pinion to one side of such point to automatically accumulate a count of operations of pinions to the other side of such point as an incident to such operations, means capable of varied manipulation to effect interruption of coöperative action of impression devices at that point and bring into play the counting means or to effect the interruption at the other point without bringing such means into play; and means for preventing accumulative coöperation between pinions and racks to one side of said latter point. 70

34. In a machine of the class described, the combination of reciprocating racks; setting-up devices for regulating the degree of movement of said racks; type-carriers movable therewith; axially alined pinions actuated by the racks; impression devices coacting with the type and coöperatively related for cipher-printing with provisions for interrupting and restoring at will the coöperative relationship at either of two predetermined points; means controlled by the setting-up devices for effecting coaction between a rack and its pinion to one side of such point to automatically accumulate a count of operations of pinions to the other side of such point as an incident to such operations, means capable of varied manipulation to effect interruption of coöperative action of impression devices at that point and bring into play the counting means or to effect the interruption at the other point without bringing such means into play; and means for preventing accumulative coöperation between pinions and racks to one side of said latter point, while preserving coöperative relationship for transfer purposes. 80

35. In a machine of the class described, the combination of reciprocating racks; type-carriers movable therewith; axially alined pinions actuated by the racks; impression devices coacting with the type and coöperatively related for cipher-printing with provisions for interrupting and restoring at will the coöperative relationship at either of two predetermined points; means for effecting coaction between a rack and its pinion to one side of such point to automatically accumulate a count of operations of pinions to the other side of such point as an incident to such operations, means capable of varied manipulation to effect interruption of coöperative action of impression devices at that point and bring into play the counting means or to effect the interruption at the other point without bringing such means into play; and means for preventing accumulative coöperation between pinions and racks to one side of said latter point, while preserving coöperative relationship for transfer purposes. 90

36. In a machine of the class described, 105

the combination of reciprocating racks; type-carriers movable therewith; axially aligned pinions actuated by the racks; impression devices coacting with the type and 5 cooperatively related for cipher-printing with provisions for interrupting and restoring at will the cooperative relationship at either of two predetermined points; means for effecting coaction between a rack and its 10 pinion to one side of such point to automatically accumulate a count of operations of pinions to the other side of such point as an incident to such operations, means capable of varied manipulation to effect interruption 15 of cooperative action of impression devices at that point and bring into play the counting means or to effect the interruption at the other point without bringing such means into play; means for preventing accumulation 20 of cooperative between pinions and racks to one side of said latter point, while preserving cooperative relationship for transfer purposes; and means controlled by 25 said manipulative means for preventing impression-actuation of type in a counting operation.

37. In a machine of the class described, the combination of reciprocating racks; type-carriers movable therewith; axially 30 aligned pinions actuated by the racks; impression devices coacting with the type and cooperatively related for cipher-printing with provisions for interrupting and restoring at will the cooperative relationship at a 35 predetermined point; means for effecting coaction between a rack and its pinion to one side of such point to automatically accumulate a count of operations of pinions to the other side of such point as an incident to 40 such operations, means capable of varied manipulation to effect interruption in cooperative action of impression devices with or without bringing into play said counting means; means for preventing accumulation 45 of cooperative between pinions and racks to one side of such point of interruption, when the counting means is not brought into play, and means for causing backward turning of 50 pinions to set up type on both sides of such point of interruption.

38. In a machine of the class described, the combination of reciprocating racks; type-carriers movable therewith; axially aligned pinions actuated by the racks; impression 55 devices coacting with the type and cooperatively related for cipher-printing with provisions for interrupting and restoring at will the cooperative relationship at a predetermined point; means for effecting coaction between a rack and its pinion to one side of such point to automatically accumulate a count of operations of pinions to the other side of such point as an incident to 60 such operations, means capable of varied manipulation to effect interruption in co- 65

operative action of impression devices with or without bringing into play said counting means; means for preventing accumulative cooperation between pinions and racks to one side of such point of interruption, when 70 the counting means is not brought into play; and means for causing backward turning of pinions to set up type on both sides of such point of interruption, with provisions for restoring cooperative relationship between impression devices when the counting means have not been brought into play.

39. In a machine of the class described, the combination of reciprocating racks; type-carriers movable therewith; axially 80 aligned pinions actuated by the racks; impression devices coacting with the type and cooperatively related for cipher-printing with provisions for interrupting and restoring at will the cooperative relationship at a 85 predetermined point; means for effecting coaction between a rack and its pinion to one side of such point to automatically accumulate a count of operations of pinions to the other side of such point as an incident to 90 such operations, means capable of varied manipulation to effect interruption in cooperative action of impression devices with or without bringing into play said counting means; means for preventing accumulative 95 cooperation between pinions and racks to one side of such point of interruption, when the counting means is not brought into play, while preserving cooperative relationship for transfer purposes; and means for causing backward turning of pinions to set up type on both sides of such point of interruption.

40. In a machine of the class described, the combination of reciprocating racks; type-carriers movable therewith; axially aligned pinions actuated by the racks; impression devices coacting with the type and cooperatively related for cipher-printing with provisions for interrupting and restoring at will the cooperative relationship at a 105 predetermined point; means for effecting coaction between a rack and its pinion to one side of such point to automatically accumulate a count of operations of pinions to the other side of such point as an incident to 110 such operations, means capable of varied manipulation to effect interruption in cooperative action of impression devices with or without bringing into play said counting means; means for preventing accumulative 115 cooperation between pinions and racks to one side of such point of interruption, when the counting means is not brought into play, while preserving cooperative relationship for transfer purposes; and means for causing backward turning of pinions to set up type on both sides of such point of interruption, with provisions for restoring cooperative relationship between impression devices when the counting means have not been brought into play.

1 vices when the counting means have not been brought into play.

41. In a machine of the class described, the combination of reciprocating racks; type-carriers movable therewith; axially alined pinions actuated by the racks; impression devices coacting with the type and coöperatively related for cipher-printing with provisions for interrupting and restoring at will the coöperative relationship at either of two predetermined points; means for effecting coaction between a rack and its pinion to one side of such point to automatically accumulate a count of operations of pinions to the other side of such point as an incident to such operations, means capable of varied manipulation to effect interruption in co-operative action of impression devices with or without bringing into play said counting means; means controlled by said manipulative means for preventing impression-actuation of type set in a counting operation; means for preventing accumulative coöperation between pinions and racks to one side of such point of interruption, when the counting means is not brought into play; and means for causing backward turning of pinions to set up type on both sides of such point of interruption.
42. In a machine of the class described, the combination of reciprocating racks; type-carriers movable therewith; axially alined pinions actuated by the racks; impression devices co-acting with the type and coöperatively related for cipher-printing with provisions for interrupting and restoring at will the coöperative relationship at either of two predetermined points; means for effecting coaction between a rack and its pinion to one side of such point to automatically accumulate a count of operations of pinions to the other side of such point as an incident to such operations; means capable of varied manipulation to effect interruption in co-operative action of impression devices with or without bringing into play said counting means; means controlled by said manipulative means for preventing impression-actuation of type set in a counting operation; means for preventing accumulative coöperation between pinions and racks to one side of such point of interruption, when the counting means is not brought into play; and means for causing backward turning of pinions to set up type on both sides of such point of interruption, with provisions for restoring coöperative relationship between impression devices when the counting means have not been brought into play.

43. In a machine of the class described, the combination of reciprocating racks; type-carriers movable therewith; axially alined pinions actuated by the racks; impression devices coacting with the type and coöperatively related for cipher-printing with provisions for interrupting and restoring at will the coöperative relationship at a predetermined point; means for effecting coaction between a rack and its pinion to one

side of such point to automatically accumulate a count of operations of pinions to the other side of such point as an incident to such operations, means capable of varied manipulation to effect interruption in co-operative action of impression devices with or without bringing into play said counting means; means controlled by said manipulative means for preventing impression-actuation of type set in a counting operation; means for preventing accumulative coöperation between pinions and racks to one side of such point of interruption, when the counting means is not brought into play; and means for causing backward turning of pinions to set up type on both sides of such point of interruption.

44. In a machine of the class described, the combination of reciprocating racks; type-carriers movable therewith; axially alined pinions actuated by the racks; impression devices coacting with the type and coöperatively related for cipher-printing with provisions for interrupting and restoring at will the coöperative relationship at a predetermined point; means for effecting coaction between a rack and its pinion to one side of such point to automatically accumulate a count of operations of pinions to the other side of such point as an incident to such operations; means capable of varied manipulation to effect interruption in co-operative action of impression devices with or without bringing into play said counting means; means controlled by said manipulative means for preventing impression-actuation of type set in a counting operation; means for preventing accumulative coöperation between pinions and racks to one side of such point of interruption, when the counting means is not brought into play; and means for causing backward turning of pinions to set up type on both sides of such point of interruption, with provisions for restoring coöperative relationship between impression devices when the counting means have not been brought into play.

45. In a machine of the class described, the combination of reciprocating racks; type-carriers movable therewith; axially alined pinions actuated by the racks; impression devices coacting with the type and coöperatively related for cipher-printing with provisions for interrupting and restoring at will the coöperative relationship at a predetermined point; means for effecting coaction between a rack and its pinion to one side of such point to automatically accumulate a count of operations of pinions to the other side of such point as an incident to such operations; means capable of varied manipulation to effect interruption in co-operative action of impression devices with or without bringing into play said counting means; means controlled by said manipulative means for preventing impression-actuation of type set in a counting operation; means for preventing accumulative coöperation between pinions and racks to one side of such point of interruption, when the counting means is not brought into play; and means for causing backward turning of pinions to set up type on both sides of such point of interruption, with provisions for restoring coöperative relationship between impression devices when the counting means have not been brought into play.

lative means for preventing impression-actuation of type set in a counting operation; means for preventing accumulative coöperation between pinions and racks to one side 5 of such point of interruption, when the counting means is not brought into play, while preserving coöperative relationship for transfer purposes; and means for causing backward turning of pinions to set up 10 type on both sides of such point of interruption.

46. In a machine of the class described, the combination of reciprocating racks; type-carriers movable therewith; axially 15 alined pinions actuated by the racks; impression devices coacting with the type and coöperatively related for cipher-printing with provisions for interrupting and restoring at will the coöperative relationship at 20 either of two predetermined points; means for effecting coaction between a rack and its pinion to one side of such point to automatically accumulate a count of operations of pinions to the other side of such point as an 25 incident to such operations; means capable of varied manipulation to effect interruption of coöperative action of impression devices at that point and bring into play the counting means or to effect the interruption 30 at the other point without bringing such means into play; means for preventing accumulative coöperation between pinions and racks to one side of said latter point; means controlled by said manipulative means for 35 preventing impression-actuation of type in a counting operation; and means for causing backward turning of pinions to set up type on both sides of either point of interruption.

47. In a machine of the class described, 40 the combination of reciprocating racks; type-carriers movable therewith; axially alined pinions actuated by the racks; impression devices coacting with the type and coöperatively related for cipher-printing 45 with provisions for interrupting and restoring at will the coöperative relationship at either of two predetermined points; means for effecting coaction between a rack and its pinion to one side of such point to automatically 50 accumulate a count of operations of pinions to the other side of such point as an incident to such operations; means capable of varied manipulation to effect interruption of coöperative action of impression 55 devices at that point and bring into play the counting means or to effect the interruption at the other point without bringing such means into play; means for preventing accumulative coöperation between pinions and 60 racks to one side of said latter point; means controlled by said manipulative means for preventing impression-actuation of type in a counting operation; and means for causing backward turning of pinions to set up 65 type on both sides of either point of inter-

ruption, with provisions for restoring coöperative relationship between impression devices when the counting means have not been brought into play.

48. In a machine of the class described, 70 the combination of reciprocating racks; a set of independently movable stops for each rack adapted to variously limit movement thereof; sets of keys for the respective sets of stops; a member adapted to be moved by 75 any one of said keys; a special actuator for one stop of a certain set, said actuator adapted to be acted upon by said member but normally out of operative relation thereto; manipulative means for bringing the actuator into operative relation to said member; and pinions coöperating with the racks.

49. In a machine of the class described, the combination of reciprocating racks; a set of independently movable stops for each 85 rack adapted to variously limit movement thereof; sets of keys for the respective sets of stops; a bail adapted to be rocked by any one of said keys; a special actuator for one stop of a certain set said actuator adapted to be acted upon by said bail but normally out of operative relation thereto; manipulative means for moving said actuator into operative relation to said bail; and pinions coöperating with the racks.

50. In a machine of the class described, the combination of reciprocating racks; a set of independently movable stops for each rack adapted to variously limit movement thereof; sets of keys for the respective sets 100 of stops, one stop being movable to effective position independently of its key; a swinging arm connected to that stop; a rock-plate adapted to operate said arm; a bail adapted to be swung by any one of the keys; manipulative means for moving the rock-plate into 105 position to be acted upon by said bail; and pinions coöperating with the racks.

51. In a machine of the class described, the combination of reciprocating racks; a 110 set of independently movable stops for each rack adapted to variously limit movement thereof; sets of keys for the respective sets of stops, one stop being movable to effective position independently of its key; a swinging arm connected to that stop; a spring-held rock-plate adapted to operate said arm; a bail adapted to be swung by any one of the keys; a slide-piece having a cam to act on 115 said rock-plate and move it into position to be acted upon by said bail; and pinions coöperating with the racks.

52. In a machine of the class described, the combination with printing mechanism comprising type-carriers, hammers, hammer-restraining latches, and latch-displacing pawls; of a cam-slide and a lever operated thereby, said lever having a cam-edge normally standing in the path of one of the said 125 pawls.

53. In a machine of the character described, the combination with accumulating, printing and totaling mechanisms, the printing mechanism comprising type-carriers, 5 hammers, hammer-restraining latches, and latch-displacing pawls, and the totaling mechanism, including a depressible key-lever; of a cam slide; a lever operated thereby, said lever having a cam-edge normally 10 standing in the path of one of said pawls; and an arm operated by the said key-lever to displace said cam lever.
54. In a machine of the class described, the combination of type-carriers; hammers; 15 hammer-restraining latches; means for individually displacing said latches; means for causing successive displacement thereof one by another, including coupler pieces pivotally mounted for movement alternately 20 into and out of engagement with different pairs of latches; bails overlying the coupler pieces respectively and one located above the other and engaged therewith; means for normally upholding both bails with provisions for dividing the lowering movement thereof to successively displace the coupler pieces; and means for lifting the upper bail as the lower one displaces its coupler piece.
55. In a machine of the class described, 30 the combination of type-carriers; hammers; hammer-restraining latches; means for individually displacing said latches; means for causing successive displacement thereof one by another, including coupler pieces pivotally mounted for movement alternately 35 into and out of engagement with different pairs of latches; bails overlying the coupler pieces respectively and one located above the other and engaged therewith; a vertical 40 slide bar engaged with the lower bail and normally upholding both bails; means for imparting a divided lowering movement to said bar to successively displace the coupler pieces; and means for lifting the upper bail 45 as the lower one displaces its coupler piece.
56. In a machine of the class described, the combination of type-carriers; hammers; 50 hammer-restraining latches; means for individually displacing said latches; means for causing successive displacement thereof one by another, including coupler pieces pivotally mounted for movement alternately 55 into and out of engagement with different pairs of latches; bails overlying the coupler pieces respectively and one located above the other and engaged therewith; a vertical 60 slide bar engaged with the lower bail and normally upholding both bails; a cam slide for imparting a divided lowering movement to said bar to successively displace the coupler pieces; and means for lifting the upper bail 65 as the lower one displaces its coupler piece.
57. In a machine of the class described, 65 the combination of type-carriers; hammers; hammer-restraining latches; means for individually displacing said latches; means for causing successive displacement thereof one by another, including coupler pieces pivotally mounted for movement alternately 70 into and out of engagement with different pairs of latches; bails overlying the coupler pieces respectively and one located above the other and engaged therewith; means for normally upholding both bails with provisions for dividing the lowering movement thereof to successively displace the coupler pieces; and a rock-plate acted upon by the lower bail and operating to lift the upper bail.
58. In a machine of the class described, the combination with accumulating mechanism comprising reciprocating racks and rack-carriers with slot and pin and spring connections, pawls normally resisting the 80 spring action, and pinions adapted to be turned by said racks and having projections to displace said pawls; of a special pawl normally out of effective position but adapted to move therefrom and obstruct one of the racks; and means for causing said special pawl to so move to effective position and there remain to block any transfer movement of the rack and the pinion it engages.
59. In a machine of the class described, 85 the combination with accumulating mechanism comprising reciprocating racks and rack-carriers with slot and pin and spring connections, pawls normally resisting the spring action, and pinions adapted to be 90 turned by said racks and having projections to displace said pawls; of a special pawl spring-drawn toward position for obstructing one of the racks; a superiorly spring-drawn lever normally constraining said 95 pawl to maintain it in ineffective position; and a cam-slide to operate on said lever.
60. In a machine of the class described, the combination of type-carriers; impression devices coöperatively related for the filling 100 in of ciphers, with provisions for suspending at will the coöperative relationship at a predetermined point; accumulating mechanism capable of subdivision for accumulation to one side only of such point and including transfer carrying mechanism with provisions for preserving its effectiveness throughout notwithstanding such subdivision of the accumulating mechanism; means for blocking the transfer mechanism at one 110 point; and a cam-slide which in one position effects the subdivision of the accumulating mechanism with preservation of transfer effectiveness throughout and in a different position brings into play the transfer-blocking means and in either position causes suspension of coöperative action of impression devices.
61. In a machine of the class described, 115 the combination of type-carriers; impres- 120

sion devices coöperatively related for the filling in of ciphers, with provisions for suspending at will the coöperative relationship at different points; accumulating mechanism capable of subdivision for accumulation to one side only of such point and including transfer or carrying mechanism with provisions for preserving its effectiveness throughout notwithstanding such subdivision of the accumulating mechanism; 5 means for blocking the transfer mechanism at one point; and a cam-slide which in one position effects the subdivision of the accumulating mechanism with preservation of 10 transfer effectiveness throughout and suspension of coöperative action of impression devices at one point, said slide in a different position causing suspension of coöperative action of impression devices at another 15 point and bringing into play the transfer-blocking means.

62. In a machine of the class described, the combination of type-carriers; impression-devices coöperatively related for the filling in of ciphers, with provisions for suspending at will the coöperative relationship at a predetermined point; accumulating mechanism capable of subdivision for accumulation to one side only of such point and 25 including transfer or carrying mechanism, with provisions for preserving its effectiveness throughout notwithstanding such subdivision of the accumulating mechanism; means for blocking the transfer mechanism 30 at one point; a cam-slide which in one position effects the subdivision of the accumulating mechanism with preservation of transfer effectiveness through and in a different position brings into play the transfer-blocking 35 means and in either position causes suspension of coöperative action of impression devices; means for preventing impression-actuation of type to one side of the point of suspension; and additional cam slide means 40 for rendering said preventing means effective when the first mentioned cam-slide is in the second-mentioned position.

63. In a machine of the class described, the combination of type-carriers; impression-devices coöperatively related for the filling in of ciphers, with provisions for suspending at will the coöperative relationship 50 at a predetermined point; accumulating

mechanism capable of subdivision for accumulation to one side only of such point and 55 including transfer or carrying mechanism with provisions for preserving its effectiveness throughout notwithstanding such subdivision of the accumulating mechanism; means for blocking the transfer mechanism 60 at one point; means for causing a division of the accumulating mechanism to count the operations of the remaining division; and cam slide means which under one adjustment brings into play the transfer-blocking 65 and counting means, and under a different adjustment effects the subdivision of the accumulating mechanism with preservation of transfer effectiveness throughout and under either adjustment causes suspension of co- 70 operative action of impression devices.

64. In a machine of the class described, the combination of type-carriers; impression-devices coöperatively related for the filling in of ciphers, with provision for suspending at will the coöperative relationship 75 at a predetermined point; accumulating mechanism capable of subdivision for accumulation to one side only of such point and including transfer or carrying mechanism 80 with provisions for preserving its effectiveness throughout notwithstanding such subdivision of the accumulating mechanism; means for blocking the transfer mechanism at one point; means for causing a division 85 of the accumulating mechanism to count the operations of the remaining division; cam slide means which under one adjustment brings into play the transfer blocking and counting means, and under a different ad- 90 justment effects the subdivision of the accumulating mechanism with preservation of transfer effectiveness throughout and under either adjustment causes suspension of co- 95 operative action of impression devices; means for preventing impression-actuation of type to one side of the point of suspen- 100 sion; and additional cam-slide means for rendering said preventing means effective when the first-mentioned cam slide means is under the first-mentioned adjustment.

WILLIAM J. KILPATRICK.
